To all whom it may concern:

Be it known that I, EDRIC C. As shown in the drawings, the characteristic and leading features of my design consist of the epaulet-like ornamental straps or pieces

A, which extend across the top of the stove at the sides thereof and downwardly in the front, the correspondingly-ornamented legs B, and the concave basket-like form of firepot C, as shown in the drawings.

Having described my invention, what I claim, and desire to secure by Letters Patent, is—
